UNITED STATES PATENT OFFICE.

JEROME B. RELYEAE, OF HICKSVILLE,

IMPROVEMENT IN NECK-YOKES.

Specification forming part of Letters Patent No. **159,217**,
November 7, 1874.

To all whom it may concern:

Be it known that I, JEROME B. RELYEAE, of Hicksville, in the county of Defiance and State of Ohio, have invented an Improvement in Neck-Yokes, of which the following is a specification:

The nature of this invention relates to an improvement in the construction of neck-yokes; and it consists in placing around the yoke, at the center thereof, a metallic band or clip, through which a bolt or rivet passes, securing the band to the leather, as is more fully hereinafter set forth.

Figure 1 is a perspective view of my improved neck-yoke. Fig. 2 is a perspective view of the metallic clip.

In the drawing, A represents a neck-yoke of the ordinary construction, provided with the usual depression at its center for the reception of the leather. B is a metallic band or clip placed around the yoke in said depression, over which is stitched the usual leather, C. A bolt or rivet, a, passes through the leather C and the ears of the clip B, rigidly securing them together.

By this arrangement the leather of the yoke is secured to the metallic band, so that it would not be liable to becoming loose, so that the leather, when the device is given the device.

I am desirous of securing my invention, and desire to be it known that I have invented a neck-yoke, A, and a metallic band, B, placed around the neck-yoke, and fastened to the neck-yoke, by a bolt or rivet, a, passing through the leather, C, and the metallic band, B, as set forth.

Witnessed this 26th day of November, 1874,

of constructing and securing a neck-yoke all possibility of becoming loose, so that the leather, when the device is given the device. Hinged metallic clasps have with a filigree of leather or woven the ends of the same. I dispense with the leather, when the device is given the device. Then said leather and keep.

What my invention, and desire to be it known that I have invented a neck-yoke, A, and a metallic band, B, placed around the neck-yoke, and fastened to the neck-yoke, by a bolt or rivet, a, passing through the leather, C, and the metallic band, B, as set forth.

JEROME B. RELYEAE.
